CRANKSHAFT FOR INTERNAL-COMBUSTION ENGINES

Otto Specht, Berlin-Spandau, Germany; vested in the Alien Property Custodian

Application November 23, 1940, Serial No. 366,846
In Germany September 7, 1939

6 Claims. (Cl. 74—604)

The invention relates to a crankshaft for internal combustion engines having balance masses for eliminating vibrations pendulously suspended on rollers between raceways, particularly after the manner of a centrifugal pendulum of the "bifilar" suspension type.

With these known devices with centrifugal pendulums, the position of the rollers during the starting period of the rotation, especially when the device is tuned for damping vibrations of low orders, is no longer corresponding to the geometrical conditions of the pendulum length because the inclination angle of the raceways is not sufficient to return the rollers under the action of the centrifugal force into the geometrically correct position. This has the consequence that the centers of the raceways and of the rollers do not lie on one line, so that an uncontrollable variation of the pendulum length and thus of the tuning conditions occurs. A pendulum of this kind cannot function to full satisfaction because the different mass elements of the pendulous weight would have to swing with different pendulum lengths. The deficiency becomes particularly evident if the pendulum is tuned to low vibration orders, as with such a tuning the angle of inclination within the operative range of the raceways is particularly small owing to the great length of the pendulum, so that there is no possibility of returning the rollers into the original correct position against the influence of the unavoidable friction.

These disadvantages are eliminated, according to the invention, by connecting the rollers with guides or links capable of maintaining the prescribed pendulum length. This guiding is effected in such a way that in any position of the pendulum the rollers maintain the geometrical pendulum length. When using links, these are preferably double-armed levers having their fulcrum journaled to the rollers, the free lever ends being articulated on the one hand to the pendulum weight and on the other to the rotating machine element. The most appropriate articulation points of the links at the rotating part and at the swinging weight of the pendulum arrangement are the raceway centers, which, in each pair of raceways, are at a distance of one pendulum length from the center of the associated roller. If constructional considerations do not permit such an articulation of the links, it is recommended to provide for a pivotal and movable mounting of both ends of each link at the rotating part and at the pendulous weight respectively, preferably by using a slotted guide, thus

taking into consideration the varying length. These articulation points may be placed on the center lines of the raceways at any distance but equally spaced from the respective raceway centers.

The drawing illustrates diagrammatically embodiments of the invention.

Fig. 1 shows a side elevation of a dampening device according to the invention, and

10 Fig. 2 a section taken along the line IV—IV of Fig. 1.

Fig. 3 is explanatory and refers to the device illustrated in Figs. 1 and 2.

Figs. 1 and 2 show a centrifugal bifilar pendulum, e. g., for an internal combustion engine for dampening torsional vibrations in the crankshaft. The device comprises a crank cheek 15 mounted on the crankshaft (not shown) of the engine so as to rotate, when in operation, in the plane of illustration about an axis located above the illustrated structure. A weight 17 is suspended from the radially outer end of the crank cheek 15 so as to be subjected to centrifugal force when in operation. Cheek 15 and weight 17 are joined with each other by means of rollers 1 and links or levers 3 so as to permit the weight to effect pendulous movements relative to the crank cheek. The crank cheek 15 passes through a radial opening 16 into a transversal recess 18 of the centrifugal weight 17 and is provided with projections 19 and 20. These projections 19 and 20 may be made in one piece with the crank shaft 15 or, as illustrated, may consist of separate plates attached to both sides of the cheek and secured thereto by means of bolts 21. The projections or plates 19 and 20 form outer raceways 4, while inner raceways 5 are provided in the opposed wall of the transverse recess 18 in the centrifugal weight 17. Each pair of raceways 4 and 5 is engaged by a roller 1 which is pivoted at 2 to the middle of each of a pair of double-armed levers 3. One end 6 of each lever 3 is articulately mounted on the corresponding projections of the plates 19 and 20 as at 13, while 40 the other end 7 is articulately connected with the upper part of the centrifugal weight 17 as at 12.

The function of the roller and lever mechanism will be understood from Fig. 3. The axis of the roller 1 lies in the center of the double-armed lever 3. Since the opposite ends of each lever 3 are respectively connected to the pendulum at point 12 and to the crankshaft web at 13, the roller is maintained in a definite position relative the inner and outer arcuate raceways 4 and 5, and therefore each swing of the pendulum will

take place about the prescribed path determined by said arcuate raceways. If, however, the arms 3 were not provided and the freely mounted roller 1 were permitted to slide relative to one of the surfaces 4 or 5, the prescribed path of the pendulum swing would be changed, thus changing the damping effect of the pendulum.

According to the present invention, links 3 serve as a cage for roller 1. At the point 12 where one end of the link 3 is articulated to the pendulum 17, this point is disposed along a straight line 12a, 12, 2, 13, 12b containing the radii for both arcuate surfaces 4 and 5 when the parts are in normal bold line position as shown in Fig. 3. At the point 13, the other end of link 3 is articulated to the crank cheek 19, 20 along the above-mentioned straight line 12a, 12, 2, 13, 12b, said points 12 and 13 being equidistant from point 2. Thus, it is seen that sliding or scuffing of the roller will be prevented and that the peripheral elements or roller 1 will always tangentially engage the corresponding elements of the arcuate raceway surfaces 4 and 5 when the pendulum swings from normal position.

In bifilar pendulums such as disclosed, each of the pendulum elements swings about a radius or pendulum length equal to the distance between points 12a and 12b, and therefore each position of the pendulum is always parallel to the succeeding position. In Fig. 3, the pins 12 and 13 are each located from the roller center 2 a distance less than the pendulum length 12a, 2; consequently, elongated slots 10 and 11 must be provided. The necessary length of these slots will diminish according to the proximity of pins 12 and 13 to the theoretical centers 12a and 12b. If pins 12 and 13 are located at the respective centers 12a and 12b, the slots need only to be long enough to prevent the pins from carrying any of the load supported by roller 1.

Fig. 3 is a diagrammatic view exaggerating the movement of the pendulum 17 for the sake of illustration. In operation, the pendulum actually swings back and forth through a very small arc which is only a fraction of that shown in Fig. 3. The bold line position of the parts in this view correspond with the normal position of the pendulum as shown in Fig. 1, whereas the dotted line position corresponds to a position where the pendulum 17 and point 12 have swung to the left of the position shown in Fig. 1.

I claim:

1. A rotary device for dampening vibrations, in particular in crankshafts of internal combustion engines, comprising a rotating member, a weight suspended from the radially outer end of said member so as to be subjected to centrifugal force when in operation, rollers arranged between said member and said weight, and raceways arranged on said member and said weight and engaging said rollers to permit said weight pendulous movements relative to said member, and a guiding mechanism connecting said member with said weight and engaging said rollers for constrainedly guiding said rollers to maintain a constant geometrical pendulum length in every position of said weight relative to said member, said mechanism having lost motion between said rollers, on the one hand, and said member and weight, on the other hand, in a direction perpendicular to the rolling direction of said rollers on said raceways.

2. A rotary device for dampening vibrations, in particular in crankshafts of internal combustion engines, comprising a rotating member, a

weight suspended from the radially outer end of said member so as to be subjected to centrifugal force when in operation, rollers arranged between said member and said weight, and arcuate raceways arranged on said member and said weight and engaging said rollers to permit said weight pendulous movements relative to said member, two guiding links journalled at both axial sides respectively of each roller, and means for respectively connecting each of said links with said roller, member, and said weight at points lying in a straight line containing the common radii of said raceways, whereby said roller is guided in a constrained dependence upon movements of said weight relative to said member, said link connections between said link on one hand, and said weight and member on the other comprising lost motion in a direction perpendicular to the rolling direction of said rollers on said raceways.

3. A rotary device for dampening vibrations, in particular in crankshafts of internal combustion engines, comprising a rotating member, a weight suspended from the radially outer end of said member so as to be subjected to centrifugal force when in operation, rollers arranged between said member and said weight, and cylindrical raceways arranged on said member and said weight and engaging said rollers to permit said weight pendulous movements relative to said member, and two double-arm levers arranged at both axial sides respectively of each roller, each of said levers having the ends thereof respectively journalled to said weight and to said member about an axis coaxial with the radii of said raceways when the parts are in normal position, said roller being pivotally connected to the center of said lever.

4. A rotary device for dampening vibrations, in particular in crankshafts of internal combustion engines, comprising a rotating member, a weight suspended from the radially outer end of said member so as to be subjected to centrifugal force when in operation, rollers arranged between said member and said weight, and curved raceways arranged on said member and said weight and engaging said rollers to permit said weight pendulous movements relative to said member, and two double-arm levers arranged at both axial sides respectively of each roller, means for rotatably connecting the center of each of said levers to said roller, and means for pivotally connecting the ends of each of said levers with said member and said weight respectively at points equally spaced from the roller centers, said latter points lying in a line coaxial with the radii of said raceways, and said pivotal connections having lost motion in the direction of the connecting line containing said points.

5. A rotary device for dampening vibrations, in particular in crankshafts of internal combustion engines, comprising a rotating member, a weight suspended from the radially outer end of said member so as to be subjected to centrifugal force when in operation, rollers arranged between said member and said weight, and raceways arranged on said member and said weight and engaging said rollers to permit said weight pendulous movements relative to said member, and a guiding mechanism for confining the rolling movements of said rollers relative to said member and said weight so as to maintain a constant geometrical pendulum length in every position of said weight relative to said member, said mechanism being linked to said member and to said

weight and engaging said rollers to prevent sliding movements of said rollers relative to said raceways.

6. A rotary device for dampening vibrations, in particular in crank shafts of internal combustion engines, comprising a rotating member, a weight suspended from the radially outer end of said member so as to be subjected to centrifugal force when in operation, at least one roller arranged between said member and said weight, 10

raceways arranged on said member and said weight, said raceways engaging said roller to permit pendulous movement of said weight relative to said member, and means carried by said roller and operatively connected to said member and to said weight for preventing slippage of said roller upon said raceways in every position of said weight relative to said member.

OTTO SPECHT.
